TIME ELEMENT RELAY

Oscar S. Field, Rochester, N. Y., assignor to General Railway Signal Company, Rochester, N. Y.

Application February 17, 1943, Serial No. 476,207

9 Claims. (Cl. 200—97)

This invention relates in general to electrically operated time element relays and has more particular reference to a relay of this type which is especially adapted for railroad use.

The present time element relay measures a time period in connection with controlling a circuit, or the like, and is of the general type of device as shown in the Field Patent No. 2,199,335, granted April 30, 1940, and as disclosed in the Little Patent, No. 2,272,568, granted February 10, 1942.

One of the objects of the present invention is to provide a time element relay having readily accessible means for adjusting the time period to be measured.

Another object of this invention is to provide mechanical snubbing means which is simpler and more effective than has heretofore been available.

Another object of the present invention is to provide an improved clutching and unclutching means between a driving means and a driven timing wheel which is more dependable, and at the same time simpler than has heretofore been available.

Further objects of the invention are to provide a relay of this type which is simpler yet more durable and dependable and longer lived than has heretofore been realized.

Further objects, purposes and characteristic features of the present invention will appear as the description progresses, reference being made to the accompanying drawings showing, solely by way of example, and in no manner whatsoever in a limiting sense, one form which the invention can assume. In the drawings:

Fig. 1 is a sectional view on line 1—1 of Fig. 2, and viewed in the direction of the arrows of a device in accordance with this invention.

Fig. 2 is a front elevational view, with the front cover removed, of the device of Fig. 1.

Fig. 3 is a sectional view on line 3—3 of Fig. 2, viewed in the direction of the arrows.

Fig. 4 is a sectional view, to an enlarged scale, on line 4—4 of Fig. 2, viewed in the direction of the arrows.

Fig. 5 is a schematic view of the device of Fig. 1, included in a control system to show one of its applications.

Referring now to the drawings, the relay constituting the present invention comprises a main casing MC of suitable metal, such as iron, having an open top portion normally covered by a top plate TP of suitable insulating material and detachably fastened in place as by screws 6. This top plate, in the usual manner, carries various

terminals posts, as 7, and rests on a usual gasket 8. The front end of the main casing is open and is normally covered by a front plate FP detachably held in place by means such as screws 9.

5 The front plate is normally covered with a cupped front cover FC made preferably of suitable transparent material, such as glass or the like. This front cover is held in place by long threaded studs 10 passing through plate FP and screwing into receiving sockets in lugs 11 on the main casing and receiving spring pressed thumb nuts 12 at their outer ends sealed in place by detachable seals as 13. This front casing rests on a gasket 14 and is securely held in place by the 15 connecting means just described.

As shown most clearly in Fig. 4, the front plate FP has an aperture therein which is normally covered by a cover plate CP securely held in place by screws 16, and this cover plate carries a forwardly projecting shaft S having portions 17, 18, 19 and 20 of different diameters. This shaft S carries a timing wheel TW which is toothed around its periphery, as at 21, and is fastened rigidly to an inner thimble 22 which is received 20 on the portion 19 of shaft S whereby the timing wheel and its thimble can turn on shaft S, which shaft of course cannot turn, since it is rigidly connected to the center plate CP. Fastened to the timing wheel, as by rivets 23, is a biasing spring 24 which embraces the portion 18 of shaft S and contains within itself and surrounding this portion 18, a spiral biasing spring 25, which spring is connected at its outer end to the spring housing as by a pin 26. The spring is connected at its inner end to an inturned lip 27 of an adjusting plate 28 which is rotatable on the portion 17 of shaft S, and can be held in any desired adjusted position by means of a screw 29, the inner end of which fits into any one of a series of notches 30 in the periphery of wheel 28. Thus, the tension of the biasing spring can be readily adjusted to any desired value by the means described just above.

45 The timing wheel normally engages a timing contactor 32, which has a detent 33, which is engageable in any one of the teeth 21 of the timing wheel, and when so engaged, the contactor 32 and the timing wheel are constrained to move together.

50 The contactor 32 is mounted on an arm 34 connected as by rivets 35, for example, to a disc-like collar 36 forming part of an outer thimble 37 which is slidably and rotatably received on the thimble 22. This thimble 37 is hollow, as shown, 55 to receive a biasing spring 38, of a helical form,

with one end of the spring bearing against the inner end of thimble 37, and the other end bearing against the outer face of the timing wheel.

Mounted on the hollow thimble 37 is a mechanical snubbing member 40 in the form of a relatively heavy thick disc. This snubbing member is pressed by a cupped triangular spring plate 41 against the outer face of flange 36 whereby to produce a frictional effect when these two faces move relatively to each other. The spring plate 41 is held in place behind a cupped washer 42 which in turn is held in place on the outer thimble by a split washer 43.

The thimble 37 is held against moving too far in a forward direction by means of a split washer 44 cupped into the outer end of the thimble 37 and received in a circulate groove in the inner thimble 22.

The inner thimble 22 in its turn, is held against moving forwardly too far by means of a washer 45 on portion 20 held in place by a cotter pin or the like, 46.

As thus far described, it can be seen that a timing wheel is provided with a biasing spring which is adjustable in a ready manner, and that the timing wheel is normally engaged with a contactor which is mounted on a thimble. Also, this thimble can be snubbed by a snubbing weight 40 when the motion of the thimble is suddenly stopped, as is the case when the contactor strikes contacts with which it cooperates, as will appear from the description to follow.

The drive means for driving the timing wheel is shown as comprising a motor M which can be of any suitable, relatively constant speed, type, and can, for example, be a direct current constant speed motor such as shown, for example, in the Field patent, No. 2,263,331, granted November 18, 1941; or the Field Patent No. 2,206,667 granted July 2, 1940. This motor, as shown in Fig. 1, is connected to the front plate FP as by screws 48 and includes a gear train in a housing 49 for driving a stub shaft 50 to which is pinned a drive gear 51.

For controlling the connection of the drive to the timing wheel, there is employed an electromagnet EM which includes pole shoes 53 connected to the front plate by means of screws 54 passing through the front plate and into the pole shoes.

Between the front plate and the pole shoes, is a U-shaped support bracket with the base of the U clamped between the pole shoes and the rear face of the front plate and with the legs as 55 and 56 extending rearwardly of the main casing. for strengthening purposes, the rear ends of legs 55 and 56 are connected together by a tie plate 57.

The armature 58, cooperating with pole shoes 53, is connected to a support arm at each end as at 59 at the one end, which arms are pivoted to the inner faces of the ends of the U bracket as at 60 for arm 59, whereby the armature is pivoted so as to readily move to attracted and retracted positions.

The armature is limited in movement in its retracted position by two unturned lips, 60¹ and 61, formed on the lower edge of the arms of the U bracket. In its attracted position, armature 58 is limited in movement by the contacting of an adjustable screw or residual pin 59¹, carried by the armature, with the unturned lip 61¹ on the edge of the base member of the U bracket and is positioned between the two pole shoes, as shown more clearly in Fig. 3.

The armature 58, in moving from retracted to attracted position, functions to engage the motor M with the timing wheel by means of a gear and lever connection. This includes a central, outwardly extending arm 62, fastened to the armature as at 63, and carrying in an adjustable manner at its outer end, a threaded vertical member 64 to which is pivoted at 65 an upwardly extending member 66. This member 66 is pivoted as at 67 to a right-angled frame member having a vertical leg 68 and a horizontal leg 69. The frame member, at its angle point, carries a pinion 71 which is always in mesh with the drive pinion 51 carried on the motor stub shaft 50. Shaft 50 passes through the horizontal arm 69 of the angle bracket, which bracket is suitably held in place thereon, as shown.

The parts are so arranged that when the armature is in retracted position, pinion 71 is out of mesh with timing wheel TW. When, however, armature 58 is moved to attracted position, the angle frame pivots on the motor drive shaft 50, to bring pinion 71 into mesh with the timing wheel, to thereby turn the timing wheel in a clock-wise direction, as indicated by the arrow 72, for the purpose of controlling various contacts, as will appear as the description progresses.

As shown in Fig. 1, a resistance unit Res is connected in series in the energizing circuit for the motor M and can be readily replaced by larger or smaller resistance units in accordance with the applied voltage, in order to protect the motor against overheating.

Also, as shown in Fig. 1, there is a rectifier Rec connected in series with the energizing circuit for the electromagnet EM, which functions to prevent operation of the device if the improper polarity of current be applied thereto. This rectifier is mounted on a stud 75 which is carried by a support bracket 76 connected to the main casing, as by screws 77. This stud passes through, and supports the back yoke 78 of the electromagnets, and thus the magnets which are at their forward ends are supported by the front plate.

The contactor 32 which, as described above, is moved during operation of the device by the timing wheel, cooperates with various sets of contacts which it bridges across for completing circuits.

As shown particularly in Figs. 2 and 5, there is a pair of check contacts 79 and 80 which are normally bridged across by a contactor 120 on the timing wheel, when it is biased to its unoperated position by the biasing spring. These contacts 79 and 80 are carried by contact fingers as 81 and 81¹ held in an insulating block 82, carried by the front plate by means of bolts 83. These contact fingers are limited in movement in a counter-clockwise direction, as viewed in Fig. 2, by a stop pin 84 carried by the front plate.

A second pair of contacts which function as timing contacts 85 and 86 are carried by contact fingers 87 and 88 which are held in an insulating block 89 held on the front plate by bolts 90. These contact fingers, as well as the check contact fingers, are furnished with stop plates as 92 and 93. Also, carried by the block 89 is an overrun set of contacts 94 and 95, equipped with a pusher 96 having a lost motion connection with the fingers 87 and 88, whereby, if the contactor 32, after bridging across the contacts 85 and 86, continues to travel but a short distance, the pusher 96 operates to open the overrun contacts

94-95 and break the motor energizing circuit, as will appear more clearly in the following description.

This timing device is arranged for facilitating changing of the timing period to be measured by the device. This is accomplished by a wrench member W which is held in a sleeve 97, held in place by a nut 98 in an opening in the front cover. This wrench is sealed against operation, as by seal 99, to prevent unauthorized changing of the timing period.

When it is desired to change the timing period, either to increase or decrease it, the seal 99 can be broken and the wrench W can be pushed inwardly to engage the wrench slot 100 in the outer thimble which can be pushed inwardly against the pressure of spring 38 to disengage contactor 32 from the detent 33 on the timing wheel. The wrench can then be turned to turn the contactor 32 with respect to the timing wheel in either direction, and then the wrench can be withdrawn to permit reengagement or remeshing of the contactor and the timing wheel. The contactor arm carries an indicator 101 for convenience in adjusting the timing period, and this indicator cooperates with various arbitrary marks 102 about the periphery of the timing wheel.

The adjusting means for the timing wheel biasing spring 25 is employed for initially adjusting the tension of this spring, during manufacture, to insure proper contact pressure between the contactor 120 and the check contacts when the device is deenergized.

In Fig. 5 is shown, in a wholly diagrammatic manner, one of the many applications for which this timer is adapted. This application relates to the control of a track switch at a siding and is so arranged as to prevent danger of the switch being moved in the path of an oncoming train.

As shown in Fig. 5, there is a stretch of single track separated into electrically isolated sections to constitute an approach track section AT and a detector track section DT. A siding 105 connects to the detector track section by a track switch TS, which can be controlled by a power-operated switch machine SM, which in turn is controlled through a circuit including a contact finger 106 and front point of a lock relay LR.

Associated with the approach track section is an approach track relay ATR, and in like manner associated with the detector track section is a detector track relay DTR. An approach relay AR is employed in the system and is energized through a circuit including contact finger 107, and front point, of relay ATR, and various approach selection contacts, indicated as 108, and which can be of any usual character. At the entrance to the detector track section, traffic being considered in the direction of the arrow 109, is a wayside signal S2 having upper arm S2a and a lower arm S2b controlling, respectively, the main line track and the turn-out. This signal can be manually controlled, subject, of course, to traffic conditions. As shown, there is a signal-at-stop relay MR which is energized through a circuit which includes signal contactors 110 and 111, closed when the respective signal arms are at stop. A relay ASR, an approach stick relay, is employed in the system for purposes which will appear as the description progresses.

On setting up a route, the signal is of course cleared, and this causes the release of relay MR, which in turn causes the release of the approach stick relay ASR as is obvious from the showing of Fig. 5. This does not, however, initiate the

timer because, although contact finger 112 has made up its back point, there is no energy on wire 113 for energizing the motor and electro-magnet of the timer, since the source is disconnected at contact finger 114 of relay MR which, it should be recalled, is at this time in released position.

If now it be desired to change the route already set up, the signals are first put to stop, after 10 which the switch is moved to the desired new position. If, at this time, the approach section is not occupied, then the approach relay AR is in attracted position so that putting the signals to stop and the subsequent picking up of relay 15 MR puts energy through contact finger 114 and front point on the timer tending to initiate the same. The timer, however, is not initiated since it is slow enough to respond to energy, to permit the approach stick relay ASR to pick up through 20 contact finger 116 and front point of the approach relay AR to thereby remove energy from the timer.

If, however, at the time the route is to be changed, the approach track section is occupied, 25 the approach relay AR is in released position, and with the approach stick relay ASR in released position, due to the previous clearing of the signals, and with the relay MR in attracted position, due to the subsequent placing of the signals at 30 stop, energy is placed on the timer energizing wire 113, through a front point of relay MR and a back point of relay ASR, to initiate the timer by energizing in multiple the electro-magnet EM and the motor M. It should be here noted that 35 energy of the incorrect polarity will not energize the electro-magnet due to the rectifier Rec. Also, the resistance Res in the motor circuit is selected to be of a proper value with respect to the applied voltage, so as to protect the motor 40 against damage from overheating.

If the detector track section DT had been occupied at the time it was desired to change the route, relay DTR would have been in released position and relay ASR would have been restored to 45 attracted position through a circuit including contact finger 118 and back point of relay DTR, whereby to prevent the initiation of the timer. This is wholly proper and safe since the detector track section relay DTR, in released position, has 50 opened the energizing circuit for the lock relay LR at contact finger 119, and hence, control of the switch machine through its energizing circuit is withheld. In this same situation, should there also be an approaching train on the section AT so that relay AR is in released position, the timer still is not initiated, and this is wholly proper since the train on the approach section is faced with a stop signal due to the above referred to occupancy of the detector track section, and hence, is presumably under control so as to 55 stop before reaching the turn-out.

Consider, now, the operation when the time element device is initiated, as set forth above, by the motor and the electro-magnet being energized in multiple. Upon the electro-magnet being 60 energized, it picks up its armature to connect the drive from the motor to the timing wheel, and the timing wheel moves at a uniform rate in a clockwise direction. The contactor 32 is carried 65 with the wheel and, after a predetermined period of time, dependent upon the adjustment, as referred to above, contactor 32 bridges across timing contacts 85 and 86 to close an energizing circuit for the approach stick relay ASR which is 70 obvious from the drawings to thus cause picking 75

up of relay ASR, and hence to break the energizing circuit for the timer. Upon picking up, relay ASR is stuck up through a stick circuit including its contact finger 112 and front point and contact finger 114 of front point of relay MR.

Upon being deenergized, the timer wheel returns under the urge of its returning spring to the initial position in a practically instantaneous manner, to reclose the check contacts 79 and 83 and thereby complete an energizing circuit for the lock relay LR which includes these check contacts in closed position, the contact finger 119 and front point of the detector track relay DTR, the contact finger 123 and front point of relay ASR, and contact finger 114 and front point of relay MR. With the lock relay LR in picked up position, the switch machine can be controlled at will to move the track switch and set up the desired changed route.

The overrun contacts are operated as soon as sufficient contact pressure has been built up between contactor 32 and contacts 85 and 86, and the gap between pusher 96 and contact finger 87 is for the purpose of first permitting the building up of this contact pressure. These contacts 94 and 95 are employed to cut off energy from motor M, while leaving energy on the electro-magnet EM and the drive-in mesh, where the timer is employed in connections other than with a relay, as the relay ASR.

When employed in connection with an approach stick relay, as ASR, should the relay fail to pick up upon closure of the timing contacts, the motor is nevertheless deenergized.

It is of course to be understood that, under certain conditions, the overrun contacts can be adjusted to normally open, so as to furnish an additional safeguard against the system operating beyond the contemplated proper point.

The above specific description of one form which the present invention can assume has been given solely by way of example, and is not intended, in any manner whatsoever, in a limiting sense. It is to be understood that various modifications, adaptations and alterations may be applied to meet the requirements of practice without in any manner departing from the spirit or scope of the invention, except as limited by the appended claims.

What I claim is:

1. In a time element relay, in combination, a front plate, a shaft carried by the plate, a peripherally toothed timing wheel rotatable on the shaft, a timing contactor rotatable and slidable on the shaft, a fixed time contact engageable by the timing contactor, means for rotatably driving the timing wheel, a tooth on the contactor engageable with any of the teeth on the wheel, means biasing the contactor to position its tooth in engagement with a wheel tooth, a completely enclosing relay casing, and adjusting wrench means operable from outside of the enclosing casing for sliding the contactor on the shaft so as to disengage its tooth from the wheel and for then turning the contactor on the shaft relatively to the wheel, and then permitting reengagement of the tooth with the wheel.

2. In a time element relay, in combination, a front plate, a shaft carried by the plate, a peripherally toothed timing wheel rotatable on the shaft, a timing contactor rotatable and slidable on the shaft, a fixed time contact engageable by the timing contactor, means for rotatably driving the timing wheel, a tooth on the contactor engageable with any of the teeth on the wheel,

means biasing the contactor to position its tooth in engagement with a wheel tooth, adjusting means operable for sliding the contactor on the shaft so as to disengage its tooth from the wheel and for then turning the contactor on the shaft relatively to the wheel, and then permitting reengagement of the tooth with the wheel, a thimble fixed to the contactor and rotatable and slidable on the shaft, an upstanding flange on one end of the thimble, a snubbing wheel slidable and rotatable on the thimble, and elastic means at the other end of the thimble biasing the snubbing wheel against said flange, whereby to snub the timing wheel upon the contactor striking the fixed contact.

3. In a time element relay, in combination, a front plate, a shaft carried by the plate, a peripherally toothed timing wheel rotatable on the shaft, a timing contactor rotatable and slidable on the shaft, a fixed time contact engageable by the timing contactor, means for rotatably driving the timing wheel, a tooth on the contactor engageable with any of the teeth on the wheel, means biasing the contactor to position its tooth in engagement with a wheel tooth, a completely enclosing relay casing, adjusting wrench means operable from outside of the enclosing casing for sliding the contactor on the shaft so as to disengage its tooth from the wheel and for then turning the contactor on the shaft relatively to the wheel and then permitting reengagement of the tooth with the wheel, a thimble fixed to the contactor and rotatable and slidable on the shaft, an upstanding flange on one end of the thimble, a snubbing wheel slidable and rotatable on the thimble, and readily removable elastic means at the other end of the thimble biasing the snubbing wheel against said flange whereby to snub the timing wheel upon the contactor striking the fixed contact.

4. In a time element relay, in combination, a support plate, a stub shaft carried by the plate, an inner thimble rotatable and non-slidable on the shaft, an outer thimble slidable and rotatable on the inner thimble, a peripherally toothed timing wheel fixed to the inner thimble, elastic means biasing the wheel to an initial rotative position, a timing contactor fixed to the outer thimble, a tooth on the contactor engageable with any of the teeth on the wheel, means biasing the contactor and outer thimble lengthwise of the shaft to position the tooth in engagement with the wheel, the contactor and outer thimble being slidable against its biasing means to disengage its tooth from the wheel.

5. In a time element relay, in combination, a support plate, a stub shaft carried by the plate, an inner thimble rotatable and non-slidable on the shaft, an outer thimble slidable and rotatable on the inner thimble, a peripherally toothed timing wheel fixed to the inner thimble, means biasing the wheel to an initial rotative position, a timing contactor fixed to the outer thimble, a tooth on the contactor engageable with any of the teeth on the wheel, means biasing the contactor and outer thimble lengthwise of the shaft to position the tooth in engagement with the wheel, the contactor and outer thimble being slidable against its biasing means to disengage its tooth from the wheel, a lateral flange on one end of the outer thimble, a snubbing wheel slidably and rotatable on the outer thimble, and means slidably biasing the snubbing wheel against the flange.

6. In a time element relay, in combination, a

support plate, a stub shaft carried by the plate, an inner thimble rotatable and non-slidable on the shaft, an outer thimble slidable and rotatable on the inner thimble, a peripherally toothed timing wheel fixed to the inner thimble, means biasing the wheel to an initial rotative position, a timing contactor fixed to the outer thimble, a tooth on the contactor engageable with any of the teeth on the wheel, means biasing the contactor and outer thimble lengthwise of the shaft to position the tooth in engagement with the wheel, the contactor and outer thimble being slidable against its biasing means to disengage its tooth from the wheel, a lateral flange on one end of the outer thimble, a snubbing wheel slidable and rotatable on the outer thimble, means slidably biasing the snubbing wheel against the flange, a completely enclosing relay casing, an adjusting wrench slidable and rotatable in the casing with its operating handle extending to the outside of the casing, the wrench being positioned, upon sliding it inwardly of the casing, to engage the outer thimble for sliding and rotation of the thimble.

7. In a motor driven timing device, a rotatable timing gear, resilient means for biasing said timing gear in one direction toward a fixed initial position, check contacts operated by said timing gear only when it is in said fixed initial position, control contacts associated with said timing gear, operating means adjustably attached to said timing gear so as to be manually adjustable to different selected positions around the axis of said timing gear to determine the amount of rotation of said timing gear away from said fixed initial position required to effect the operation of said control contacts, a substantially constant speed motor, a clutch means acting when energized to operatively connect said motor to said timing gear, control circuit means for energizing said clutch means and said motor to cause operation of said timing gear away from said fixed initial position in a direction opposite to its bias to effect the operation of said control contacts after a measured time determined by the selected position of said operating means, and means governed by the operation of said control contacts for deenergizing said clutch means to disengage said motor to permit the restoration of said timing gear to said fixed initial position by said resilient biasing means for indicating the completion of a timing operation only if said timing gear actually assumes said fixed initial position and said check contacts are operated.

8. In a motor driven timing device, a rotatable shaft, a timing gear non-rotatably mounted on said shaft, resilient means for biasing said timing gear toward a fixed initial position, check contacts operated by said timing gear only when it is in said fixed initial position, control contacts associated with said timing gear, operating means adjustably attached to said timing gear so as to be manually moved to different selected positions around the axis of said timing gear to determine the amount of rotation of said timing gear away from said fixed initial position required to effect the operation of said control contacts, a snubbing wheel mounted on said shaft and rotatable relative thereto, means for producing a predetermined amount of friction between said snubbing

wheel and said shaft during any relative movement so that said snubbing wheel can move relative to said shaft due to the inertia of the snubbing wheel when said timing gear is stopped at said fixed initial position upon its restoration, a substantially constant speed motor, a clutch means effective when actuated to operatively connect said motor to said timing gear, control means for actuating said clutch means and energizing said motor to cause operation of said timing gear away from said fixed initial position in a direction opposite to its bias to cause operation of said control contacts after a measured time determined by the selected position of said operating means, and means governed by the operation of said control contacts for rendering said clutch means inactive to disengage said motor to permit the restoration of said timing gear to said fixed initial position by said resilient biasing means to operate said check contacts for indicating the completion of a timing operation only if said timing gear actually assumes said fixed initial position, whereby said snubbing wheel acts upon the restoration of said timing gear to said fixed initial position to exert a turning force on said shaft to maintain said checking contacts operated in spite of any tendency of said timing gear to rebound away from said initial position.

9. In a motor driven time measuring organization, a rotatable shaft, a timing gear non-rotatably mounted on said shaft, check contacts associated with said timing gear, resilient means for biasing said timing gear toward a fixed normal position in which it is effective to close said check contacts, a substantially constant speed motor, a clutch means acting when energized to operatively connect said motor to said timing gear, control means at times rendered effective for energizing both said clutch means and said motor to cause the operation of said timing gear away from its initial fixed position against the bias of said resilient means to measure time, control contacts associated with said timing gear and caused to be operated thereby when said timing gear has been operated a predetermined distance away from said normal position, a snubbing wheel rotatably mounted on said shaft, means for producing a predetermined amount of friction between said snubbing wheel and said shaft during any relative movement, means acting in response to the closure of said control contacts for causing said control means to deenergize both said motor and said clutch means to thereby permit the relatively quick restoration of said timing gear to said normal position to effect the operation of said check contacts, and circuit means electrically governed by the operation of said control contacts a predetermined time after said control means is initially rendered effective only providing said check contacts are subsequently operated, whereby the timing operation required to govern said circuit means is assured of always including the operation of said timing gear through said predetermined distance, and whereby the operation of said check contacts is positive by reason of the damping action of said snubbing wheel irrespective of the tendency of said timing gear to rebound when suddenly stopped at said fixed normal position.

OSCAR S. FIELD.
